(**) Term: **14 Years**

(57) **CLAIM**

(21) Appl. No.: **29/249,880**

A wave configuration for the web of a level frame, as shown and described.

(22) Filed: **Oct. 25, 2006**

DESCRIPTION

(51) **LOC (8) Cl.** **10-04**

FIG. 1 is an isometric view of a level incorporating a web incorporating my new design, wherein the phantom lines indicate environment and form no part of the claimed design and wherein the break lines indicate indeterminate length; FIG. 2 is a side elevation view thereof;

(52) **U.S. Cl.** **D10/74; D10/69**

FIG. 3 is a top plan view thereof;

(58) **Field of Classification Search** D10/69,

FIG. 4 is a bottom plan view thereof;

D10/74; 33/365, 366.11–366.27, 367–391

FIG. 5 is an end elevation view thereof; and, FIG. 6 is a section view thereof, with reference to line 6—6 of FIG. 1.

See application file for complete search history.
